US00D631970S

(12) **United States Design Patent**
Held

(10) **Patent No.:** **US D631,970 S**
(45) **Date of Patent:** **** Feb. 1, 2011**

(54) **SYSTEM HEAD OF A CEILING MOUNTED SUPPORT SYSTEM**

D603,518 S * 11/2009 Zafar D24/185
D605,296 S * 12/2009 Hosey et al. D24/184

(75) Inventor: **Fred Held**, Hamburg (DE)

* cited by examiner

(73) Assignee: **Trumpf Medizin Systeme GmbH + Co. KG**, Puchheim

Primary Examiner—T. Chase Nelson

Assistant Examiner—Mark Cavanna

(**) Term: **14 Years**

(74) *Attorney, Agent, or Firm*—Fish & Richardson P.C.

(21) Appl. No.: **29/361,217**

(57) **CLAIM**

(22) Filed: **May 7, 2010**

The ornamental design for a system head of a ceiling mounted support system, substantially as shown and described.

(51) **LOC (9) Cl.** **24-02**

DESCRIPTION

(52) **U.S. Cl.** **D24/185**

FIG. 1 is a perspective view of the first embodiment of a system head of a ceiling mounted support system showing my new design;

(58) **Field of Classification Search** D24/176-177,
D24/184-185, 232, 234, 128; D13/122,
D13/125, 133, 139.4, 146, 151-152, 162,
D13/240; 211/70.6; 439/607-610, 638,
439/650, 676; 248/281.11; 378/194; D10/75,
D10/81

FIG. 2 is a front view thereof;

See application file for complete search history.

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an enlarged perspective view of a second embodiment of a system head of a ceiling mounted support system;

FIG. 9 is a greatly enlarged perspective view of a third embodiment of a system head of a ceiling mounted support system;

FIG. 10 is a perspective view of a forth embodiment system head of a ceiling mounted support system; and,

FIG. 11 is an enlarged perspective view of a fifth embodiment a system head of a ceiling mounted support system.

The features shown in broken lines are environmental structure and form no part of the claimed design.

The top and bottom views of the second through fifth embodiments of my design are the same as the top and bottom views, respectively, of the first example.
